PUMP

Mark J. Goldberg, Muskegon Heights, Mich., assignor to Campbell, Wyant and Cannon Foundry Company, Norton Township, Mich., a corporation of Michigan

Application July 13, 1936, Serial No. 90,277

2 Claims. (Cl. 103—37)

The present invention relates to pumps for intermittently forcing fluid fuel into the combustion chambers of internal-combustion engines; and its object is, generally, to provide a pump structure of a type like my invention shown in Patent No. 1,993,369, and improved as hereinafter appearing; and more particularly, to provide such a pump of strong and simple construction whose parts may be readily assembled and disassembled; 5 and further, to provide such a pump provided with improved adjustable means for accurately regulating the amount of fuel pumped to the engine; and further, to provide such a pump whose operating parts are located and related in 10 an improved manner facilitating the ready assembling and disassembling thereof.

These and any other and more specific objects hereinafter appearing are attained by, and the invention finds preferable embodiment in, the 20 illustrative structure particularly described in the body of this specification and illustrated by the accompanying drawings, in which:

Figure 1 is an axially sectional view of a pump structure embodying my invention;

25 Figure 2 is a transverse sectional view of certain parts thereof taken on line 2—2 of Figure 1; and

Figure 3 is a transverse sectional view of other parts taken on line 3—3 of Figure 1.

30 In the embodiment of the invention illustrated by these drawings a pump structure is shown having a body or housing comprising an upper member 1 and a lower member 2 rigidly but detachably fastened together. The upper member 1 has parallel bores 3, 4 having wider upper portions 5, 6 respectively and narrower lower portions 7, 8, and the lower member 2 has wide bores 9, 10 axially aligned with the bores 3, 4 respectively.

40 A cage 11 removably seated in bore 3 of said upper member with its collar portion 12 resting on the shoulder 13 extends downwardly into bore 9, and in its bore 14 the pumping plunger 15 slidably bears. A hollow cylindrical element 16 45 bears slidably in bore 9, its bottom 17 abutting the lower end of said plunger which has a collar portion 18 carrying a ring 19 between which and the underside of the structure's upper member 1 the helical spring 20 presses.

50 A plug 21 is threaded at 22 in the bore 3 of said upper member 1 and holds between it and the upper end of cage 11 the valve seat member 23 having a bore in which the stem 24 of the discharge valve 25 is slidable, this valve seating 55 at 26 on the upper end of this member 23 and

its stem having the longitudinal fluid passages 27. A helical spring 28 presses between this valve and the cover 29 of the plug's bore 30, held tightly in place by the cap 31 threaded at 32 on said plug and having an opening 33 through which the shank 34 of cover 29 extends, said opening communicating with the discharge pipe 35 leading to the combustion chamber of the engine (not shown).

The spring 20 which urges the plunger 15 in its intake stroke is, in the pumping stroke of said plunger compressed by the cam wheel 36 on shaft 37, driven by the engine, this wheel bearing on the bottom of the cylindrical element 16 which abutting said plunger's lower end forces the fluid 15 fuel from the pump chamber 38, opening the discharge valve 25 and overcoming its spring 28. These parts, said bores 3, 9, 14, the plunger 15, valve 25, cage 11, valve seat member 23 and cylindrical element 16 are all axially aligned.

A fluid passage 39 extending laterally from the pump chamber 38 through the cage 11 communicates through passage 40 in the structure's upper member 1 with the passage 41 extending laterally through a cage 42 into its bore 43 in which bore 43 slidably bears the accumulator plunger 44. This cage 42 removably seated in the bore 4 of the structure's upper member 1 with its collar portion 45 in said bore's wider upper portion 6 resting on the shoulder 46, extends downwardly 30 through said bore's narrower portion 8 and into the wide bore 10 in the structure's lower member 2. A hollow cylindrical element 47 slidably surrounds this cage 42 with the flat head 48 of plunger 44 lying between the lower end of this 35 cage and the bottom 49 of said element.

A helical spring 50 presses between said element's flange 51 and the ring 52 (hereinafter described) to urge said element and the accumulator plunger upwardly. A plug 53 is threaded at 54 in the bore 4 of the structure's upper member 1 and holds between it and the upper end of cage 42 the valve seat member 55 having a bore in which the stem 56 of the intake valve 57 is 45 slidable, this valve seating on the lower end of this member 55 and its stem having the longitudinal fluid passages 59. A helical spring 60 pressing between this valve and the internal shoulder 61 of the cage 42 urges said valve to closed position.

The fluid fuel is drawn into the pump through the intake pipe 62. These parts, said bores 4, 10, 43, the accumulator plunger 44, valve 57, cage 42, valve seat member 55 and cylindrical element 47 are all axially aligned. The valve seat members 55

23 and 55 have downwardly extending annular portions 63, 64 fitting in the upper ends of the bores 14, 43 of the cages 11, 42 respectively to securely hold these connected parts in alignment.

5 Cross-sectionally V-shaped rings 65, 66 of comparatively soft metal or the like are placed between the correspondingly bevelled adjacent portions of said plugs and said valve seat members respectively and provide a tight joint between 10 them.

10 A gear 70 bearing at its ends at 71, 72 is rotated by a toothed bar 73 slidably bearing at 74 and meshing with the teeth 75 of said gear. This bar may be slid manually to adjusted position 15 or by suitable governing means driven by the engine. Threaded in this gear is a member 68 carrying the stop pin 67 provided with a jam nut 69. The rotation of said gear moves this pin vertically to a position wherein its head 76 20 extending through an opening 77 in the bottom 49 of cylindrical element 47 engages the lower end of the accumulator plunger to stop its downward movement and thus gage the amount of liquid fuel pumped to the engine. To prevent 25 the member 68 from turning with the gear, the ring 52 held in place by a set screw 78 has a key tooth 79 engaging in a gap 80 in the upper turn or turns of said member's thread. A cap 81 may be removed to gain access to the stop pin for 30 adjusting it vertically relatively to the member 68.

35 By reason of the cam 36 being slowly acting, the particular embodiment of the invention illustrated by these drawings is better adapted for lower pressures than is the pump shown in said patent.

It will be seen that the parts of this pump may be readily assembled and disassembled by first disconnecting the structure's upper and lower members 1, 2; that these parts, although thus 40 readily disassembled, are very firmly and accurately held in assembled operative position; that this pump is of a very sturdy construction; and that the amount of fluid fuel pumped may be very accurately regulated.

45 The invention being intended to be pointed out in the claims, is not to be limited to or by details of construction and arrangement of the particular embodiment thereof illustrated by the drawings or hereinbefore shown or described.

50 I claim:

1. A fluid fuel pump for internal combustion engines, comprising: a housing consisting of de-

tachably connected first and second members, said first member having first and second bores and said second member having third and fourth bores coaxial with the first and second bores respectively; a first cage and a second cage 5 removably seated in the first and second bores and extending therethrough and into the third and fourth bores respectively and having coaxial therewith fifth and sixth bores respectively; removable plugs in the first and second bores 10 respectively; valve seat members in the first and second bores removably held between the plugs and the ends of the cages respectively and having end portions removably seated in the fifth and sixth bores respectively; normally closed discharge and inlet valves seating in the valve seat members in the first and second bores respectively; a pumping plunger reciprocatingly bearing in the fifth bore; an accumulator plunger reciprocatingly bearing in the sixth bore, said 15 first member having a fluid fuel passage extending therethrough and connecting the fifth and sixth bores; and means for reciprocating the pumping plunger.

2. A fluid fuel pump for internal combustion 20 engines, comprising: a housing consisting of detachably connected first and second members, said first member having first and second bores and said second member having third and fourth bores coaxial with the first and second bores respectively; a first cage and a second cage 25 removably seated in the first and second bores and extending therethrough and into the third and fourth bores respectively and having coaxial therewith fifth and sixth bores respectively; removable plugs in the first and second bores 30 respectively; valve seat members in the first and second bores removably held between the plugs and the ends of the cages respectively; normally closed discharge and inlet valves seating in the valve seat members in the first and second bores respectively; a pumping plunger reciprocatingly bearing in the fifth bore; an accumulator plunger reciprocatingly bearing in the sixth bore, said 35 first member having a fluid fuel passage extending therethrough and connecting the fifth and sixth bores; and means for reciprocating the pumping plunger, the plugs and their adjacent 40 valve seat members having bevelled adjacent ends with correspondingly shaped packing rings there- 45 between.

50 MARK J. GOLDBERG.
